FILE RACK

Leslie H. Burlin, Valparaiso, Ind., assignor to Milton L. Sturm, Evanston, Ill., doing business as Milton Sturm & Company, Chicago, Ill.

Application July 24, 1942, Serial No. 452,219

6 Claims. (Cl. 45—64)

This invention relates to file racks in general and more particularly to such file racks as are used for filing or holding magazines, papers, or letters, for ready access adjacent a chair, table, or the like.

It is one of the objects of the present invention to provide a simple rack in which magazines, papers, letters, or the like may be placed and held in position for ready access, and in which the magazines are held neatly in a vertical position regardless of how few or how many magazines or papers are placed in the rack, within the capacity of the rack.

It is a further object of the present invention to provide a rack of the above mentioned character with a movable end plate which will exert a continuous pressure against the stack of magazines or the like in the rack to hold them in position, and in which the movable plate may be tilted to allow for an examination of the contents of the rack for the selection of a particular magazine or the like.

It is a still further object of the present invention to provide a rack of the above mentioned character which is almost entirely made of wood.

It is a still further object of the present invention to provide a spring for a rack of the above mentioned character, which spring is non-metallic and yet reliable in its action.

It is a still further object of the present invention to provide a rack of the above mentioned character which is simple and economical of construction, easy to operate, and of neat and aesthetic appearance.

The attainment of the above and further objects of the present invention will be apparent from the following specification taken in conjunction with the accompanying drawings forming a part thereof.

In the drawings:

Figure 1 is a front view of a rack embodying the present invention;

Figure 2 is a top view of the rack of Figure 1;

Figure 3 is an end view of the rack of Figure 1;

Figure 4 is a transverse sectional view taken along the line 4—4 of Figure 1;

Figure 5 is a bottom view of the rack of Figure 1; and

Figure 6 is a sectional view taken along the line 6—6 of Figure 4.

Reference may now be had more particularly to the drawings, wherein like reference numerals designate like parts throughout. The rack is indicated in general by the reference numeral 1 and includes two similar end members 2—2 of

wood. Each of the end members is in the form of an inverted T and consists of a wide bottom portion 3 and a comparatively narrow upright portion 4. The two end members are secured together at their base by longitudinally extending bars 6—6. The end members 2—2 are further secured together by boards 8—8 which form the base of the rack and which are at a slight inclination to one another, as may be seen from Figure 4. The ends of the board 8—8 extend into slots in the bars 6—6. A stationary longitudinally extending vertical wall or partition 10 extends between the end members and is secured to the end members by wood screws 11—11. A pair of identical links 12—13 are pivoted to the outer side of each end member, as by a pivot screw 14. The link 13 is on the outside of the link 12. The link 13 includes an arm extending upwardly from the pivot 14 to a pivot 15 and includes an arm 18 extending in the opposite direction from the pivot 14 to a leaf spring 19 for a purpose and of a construction to be more fully set forth as this description proceeds. Likewise the link 12 includes a part 18' similar to the part 18 of the link 13 against which another spring 19 bears. An end plate member 25 on one side of the partition 10 is pivoted by the pivot screw 15 to a link 13 on one end member 2 and is pivoted by the screw 15' to a link 12 on the other end member 2. The end plate is free to swing about the pivot axis 15—15. For this purpose the screws 15—15 are in longitudinal axial alignment. The plate 25, in the position illustrated in the drawings, bears against the portion 4 of the two end members. The top of the plate 25 has a longitudinally extending outwardly curved lip 26. The plate 25 is of a length equal to the spacing between the outer surfaces of the end members 2—2. On one edge the plate 25 has an outer projection 28, as may be seen in Figure 1, which extends from the surface of the plate an amount equal to the thickness of the link 12. No such projection is present on the opposite edge of the plate 25, as is apparent from Figure 1. The two plates 25—25 on opposite sides of the partition 10 are of identical construction. Since the plates are mounted facing one another the projection 28 on one plate is on one side of the rack and on the other plate is on the other side of the rack. This may be seen from Figures 1 and 2 wherein the projection 28 on the front plate 25 is on the right hand side of the rack, as seen in Figures 1 and 2, whereas the projection 28 on the rear plate of Figure 1 is on the left hand side of the rack,

as seen in Figure 2. Thus each plate 25 is pivoted between an inner link 12 on one side of the rack and an outer link 13 on the other side of the rack. This construction permits the use of identical plates 25, whereby the manufacturer is relieved of the necessity of providing different right hand and left hand plates.

A stationary cross bar 30 is securely mounted on the underside of the rack, as by a screw 31 that threads into the base 8-8 and the partition 10. Two bars of spring wood or wooden strips 19-19 are mounted on the top of the bar 30 and extend the full length of the rack on opposite sides of the longitudinal center thereof, and project through openings 33-33 in the opposite end members 2-2. These spring bars bear against the projections 18-18' of the links 12-13 and urge the links to the position illustrated in Figure 3. When the links are in the position illustrated in Figure 3 the plates 25-25 bear against the end members 2-2 leaving a narrow opening between each plate and the partition 10 for receiving one or several magazines. If the number of magazines or papers between the partition 10 and one of the plates 25 is increased the plate is forced outwardly away from the partition 10, as illustrated in dotted lines at 40 in Figure 4. This causes the links 12-13 that support the plate involved to swing about their pivots 14-14 and force the ends of the spring members 19-19 downwardly. The spring members 19-19 thus exert a spring pressure against the part 18' of the link 12, as seen in Figure 3, and against the corresponding part 18 of the link 13 on the opposite side of the rack to urge the link to maintain the plate 25 in firm engagement against the stack of papers or magazines between the plate 25 and the partition 10, thus maintaining the magazines or papers in the rack firmly in a vertical position. If it is desired to separate some of the papers in the rack in order to select a desired magazine or paper, the plate 25 may be manually tilted about its pivot 15, as illustrated at 41 in Figure 4, to permit such separation. At all times the springs 19-19 cause the links to maintain a continuous pressure urging the plates 25 towards the partition 10.

It is to be noted that when the plate 25 is in its outwardly extended position, as illustrated in dotted lines at 40 in Figure 4, the links 12-13 that support the plate extend from the pivot 15 towards the end member 2 at a very small inclination, as indicated at 43. This is due to the curvature of the links. As a result the portion of the link at 43 serves as a closure for the open end of the magazine space between the extended plate 25 and the end member 2.

In the normal use of the rack each plate 25 is vertical and maintains pressure distributed over a large area of the last book, paper, or magazine in the rack. The plate may, however, be manually tilted, as illustrated in dotted lines at 41 in Figure 4, to permit the tops of the papers to be fanned apart, to facilitate selection of the desired paper. While the papers are fanned out at the top they are pressed together by the bottom of the plate 25, thus holding the papers in place.

In compliance with the requirements of the patent statutes I have here shown and described a preferred embodiment of my invention. It is, however, to be understood that the invention is not limited to the precise construction here

shown, the same being merely illustrative of the principles of the invention. What I consider new and desire to secure by Letters Patent is:

1. A rack comprising a base, a vertical partition secured to and extending across the base, supporting links, means adjacent the base for pivotally supporting the links, members on opposite sides of the partition pivotally mounted on the links for movement towards and away from the partition, a pair of parallel wooden spring strips mounted on the underside of the base but spaced from the underside of the base and extending lengthwise of the base for substantially the full length of the base, at least one end of each strip being free and movable away from the base, said links being engaged by the free ends of the spring strips for pressing the members towards the partition.
2. A rack for magazines or the like, comprising a base, a central longitudinal vertical partition extending above the base, means connecting the partition with the base, similar longitudinally extending plates on opposite sides of the partition, linkages supporting the respective plates, each linkage including links pivoted at the opposite ends of the rack and swingable towards and away from the partition, the plates being pivoted to the respective linkages, and spring means pressing the linkages to press the plates towards the partition.
3. A rack for magazines or the like, comprising a base, a central longitudinal vertical partition extending above the base, means connecting the partition with the base, similar longitudinally extending plates on opposite sides of the partition, linkages supporting the respective plates, each linkage including links pivoted at the opposite ends of the rack and swingable towards and away from the partition, the plates being pivoted to the respective linkages, a pair of wood spring strips secured intermediate their ends to the rack below the base and extending longitudinally of the rack to the opposite ends of the rack and each bearing against links at the two ends of the frame and biasing the links to press the plates towards the partition.
4. A rack for magazines or the like, comprising a base, a stationary longitudinal vertical wall extending above the base, means connecting the wall with the base, a pair of links pivoted to the rack at opposite ends thereof about axes in alignment with one another, a plate pivoted to the links about a horizontal axis substantially parallel to the vertical wall, a spring strip secured intermediate its ends to the rack and extending longitudinally of the rack to the ends of the rack and pressing the links in a direction urging the plate towards the vertical wall.
5. A rack for magazines or the like, comprising a base, a stationary vertical dividing wall extending above the base, said base including narrow end members at opposite ends of the dividing wall and at right angles thereto, means connecting the dividing wall and the end members with the rest of the rack, supporting links, means adjacent the base for pivotally supporting the links, a pair of end plates above the base on opposite sides of the vertical dividing wall and pivotally mounted on the links for movement towards and away from the vertical dividing wall, said end members being in the path of movement of the plates constituting stops for limiting the movement of the plates towards the vertical dividing wall, and spring means for constantly

urging the plates toward the vertical dividing wall.

6. A rack for magazines or the like comprising a base, a longitudinal vertical wall extending above the base, means connecting the base and the wall into a rigid structure, a pair of links pivoted on opposite ends of the rack, a plate member between the links and pivotally mounted

thereon and moved by the links towards and away from the vertical wall, a part of each link extending across the space between the plate and the vertical wall intermediate the top and the bottom of the plate, and spring means acting on said links to urge the plate towards the vertical wall.
